[57] CLAIM

The ornamental design for an inflatable basketball hoop
helmet, as shown and described.

DESCRIPTION

FIG. 1 is a front elevational view of an inflatable basketball
helmet showing our design;

FIG. 2 is a top plan view of an inflatable basketball
helmet showing our design;

FIG. 3 is a bottom plan view of an inflatable basketball
helmet showing our design;

FIG. 4 is a back elevational view of an inflatable basketball
helmet showing our design;

FIG. 5 is a side elevational view of an inflatable basketball
helmet showing our design, the other side being a
mirror image thereof; and,

FIG. 6 is a front perspective view of an inflatable basketball
helmet of a second embodiment showing our
new design, the broken lines are for illustrative pur-
poses, the only difference being the addition of the tabs
and the shape of the netting.

FIG. 1

FIG. 2

FIG. 3

FIG. 4

FIG. 5
